UNITED STATES PATENT OFFICE

ADRIAN S. AILES, OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT-PROTECTING DEVICE

Application filed September 26, 1927. Serial No. 222,035.

This invention relates in general to a device for protecting vaults and the like, and more particularly to a device adapted to protect the vault by means of air contaminating gases, such as tear gas or the like, and it has for an object the provision for the removal of the gas bomb during working hours, or at the user's discretion, so as to prevent an accidental discharge of the gas bomb.

Another important object of the invention is to provide such a device constructed to facilitate the removal of the gas bomb without the use of tools and without danger of exploding or releasing the bomb.

Another important object of the invention is to provide such a device which will be simple in design, efficient in operation and which may be economically manufactured.

Another important object of the invention is to provide a foolproof and dependable firing mechanism for devices of this character.

Numerous other objects and advantages of the invention will be apparent as it is better understood from the following description, which, taken in connection with the accompanying drawings, discloses a preferred embodiment thereof.

Referring to the drawings:

Figure 1 is an elevational view of the inside of a vault door and showing a device embodying my invention secured thereto in operative position;

Fig. 2 is a perspective view of the bomb container, with parts thereof separated to show details of construction;

Fig. 3 is a sectional view taken substantially on line 3—3 in Fig. 1 and showing the relative normal position of all of the parts;

Fig. 4 is a similar view, showing the firing pin released and into a bomb discharging condition;

Fig. 5 is a perspective view of the firing pin holding device; and

Fig. 6 is a perspective view of the firing pin.

While this invention is capable of employment for the protection of compartments of various sizes and characters I have shown it embodied in a device particularly adapted for attachment to the door 11 of a vault. The

bomb 16 is carried in a container 12 supported on the door 11. A cord or strand 13 is arranged over the major part of the door surface and adapted to normally prevent operation of the bomb firing mechanism and to permit operation thereof when an attempt is made to burn, cut or break through the surface of the door to gain entrance to the vault.

The receptacle 12 includes a part 14 and a part 15. The part 14 of the receptacle 12 may be of any suitable form adapted to contain a bomb 16 of any suitable type of air contaminating device and adapted to be discharged by impact. In the present instance I have shown a usual type of tear gas bomb, provided with mechanism for releasing the gas upon impact delivered to a plunger 17 carried in its top. The part 14 in the present instance is of tubular form and is provided with a bottom closure 18. It has a plurality of bayonet slots 19 in its top and a plurality of appropriately arranged openings 21 to permit the escape of gas when generated or discharged by the bomb. The receptacle part 15 is generally in the form of a cap adapted to close the upper end of the part 14 and support the entire device. It is provided with a bracket formation 22 at its rear adapted to receive a plurality of screws 23 or like fastening devices for attaching the part 15 to the door.

A pair of oppositely disposed shoulder pins 25 are driven into suitable apertures in the part 15 and are adapted to engage in the bayonet slots 19 of the part 14. The preferred form of firing device shown on the drawing includes a sleeve 26 having threaded engagement with the part 15 at 27 (Figs. 3 and 4), a closure 28 for said sleeve, a firing pin 29 slidably mounted in said sleeve, a spring 31 in said sleeve for actuating the firing pin, and a device 32 for normally preventing movement of the firing pin. The closure 28 is secured to the sleeve 26 by means of a plurality of screws 33 extending through the sleeve and having threaded engagement in the closure 28. Within the sleeve 26 and at a slight distance from an inner end 34 of the closure 28 an

annular wall 35 is secured in any suitable manner to provide a spring seat.

The firing pin may be of any suitable form and size and in the present instance I have shown such a pin having a large cylindrical portion 36 of a size permitting a free sliding fit within the sleeve 26; a portion of reduced diameter 37 above the portion 36 and providing a shoulder 38; a tapered neck portion 39; and a head portion 41 providing a shoulder 42. The normally compressed spring 31 for actuating the firing pin is disposed about the firing pin part 37 between the spring seat 35 and the shoulder 38.

The device 32 may be any suitable means for holding the firing pin in the retracted position and releasing the firing pin upon disturbance of the cord 13. In the preferred embodiment shown on the drawing this comprises a pin 43 having a sliding fit through the closure 28. This pin 43 carries a plurality of hooks 44 pivotally connected thereto by means of a pin 45 and positioned in a slot 46 in an end thereof. The end of the pin 43 opposite the hooks 44 is formed in any suitable manner to facilitate the attachment of the strand 13. I have shown this end slightly cut away and apertured at 47 to receive a ring 48 to which the strand 13 may be attached. The pin 43 is preferably apertured at 49 to receive a cotter pin or like device for locking the firing pin in retracted position during shipment or when the device is not in operation. The hooks 44 are preferably cut or punched from plate stock and formed to engage the shoulder 42 of the firing pin as shown (Fig. 3).

The pin 43 is pulled normally to the top of sleeve 26 by springs 53 interposed in the strand or cord 13 this cord being freely trained over pulleys 52. The springs 53 exert a pull on the pin 43 greater in force than that of spring 31 when the parts are in door protecting relation. The hooks 44 are engaged with the shoulder 42 of the firing pin head 41 by pushing the firing pin up into the sleeve 26 and the cord is attached. The pull on the cord 13 now holds the firing pin retracted and shoulders 51 which are provided on the hooks 44 are engaged with the bottom 34 of sleeve closure 28. This engagement positively holds the hooks in engagement with the firing pin and prevents accidental discharge.

When the cord is broken the spring 31 forces the firing pin 29 downwardly moving the pin 43 with it until the shoulders 51 engage the spring seat member 35. This engagement pulls the hooks 51 outwardly and permits the spring 31 to force the firing pin on down to fire the gas bomb.

It will be apparent that the container part 14 with the gas bomb may be readily removed when protection of the vault is not needed by merely detaching the parts 14 from the part

15, thus preventing accidental discharge while the vault is open for legitimate purposes. This removal in no way need disturb the cords or firing pin unit and the whole assembly may be rendered operative once more by merely reconnecting the container part 14 with its bomb into the cap part 15.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages the form hereinbefore described being merely a preferred embodiment thereof.

I claim:

A vault protecting device, comprising devices adapted for disturbance upon attempted unauthorized entry into the vault, an automatic discharge mechanism associated with and controlled by said devices, said discharge mechanism including a movable supporting pin, expandable shouldered hook jaws attached to said supporting pin, a capped firing pin, said jaws adapted to engage the cap of said firing pin, a spring support on said firing pin, a spring seat in said discharge mechanism, a spring located between said spring support and spring seat, the upper surface of said spring seat constructed and located to arrest the movement of said jaws and to open the same and release said firing pin, said spring arranged to drive said released firing pin toward a bomb and fire the same.

ADRIAN S. AILES.
